UNITED STATES PATENT OFFICE

ANDREW GRAHAM SHIELDS, OF ATTLEBORO, MASSACHUSETTS, ASSIGNOR TO FILL-KWIK COMPANY, OF ATTLEBORO, MASSACHUSETTS, A CORPORATION OF MASSACHUSETTS

COSMETIC-PENCIL AND MIRROR CONTAINER

Application filed July 7, 1928. Serial No. 290,953.

My invention relates to cosmetic pencil carriers and refers particularly to devices of this character in which a cosmetic pencil and a mirror may be simultaneously employed 5 without disengaging the pencil from the device.

The proper application of cosmetic pencils, such as lip-sticks, requires the employment of a mirror in order that the user may 10 be aware of the manner in which she is making such application.

This has usually been accomplished by means of a mirror and a cosmetic pencil unconnected with each other, requiring the use 15 of both hands, one to hold the mirror and the other hand to apply the pencil, and it is evident that a device that will enable the user to accomplish the desired result by the use of one hand only would be of great value and 20 convenience.

As compactness is highly desirable in devices of this character, the use of a separate mirror and a separate pencil is objectionable.

The use of separate elements is further objectionable because of the liability of one to 25 become lost, thus rendering the other element useless for the desired purpose.

Another objectionable feature of the described devices is that the cosmetic-pencil 30 holder must have a cover for its open end in order to protect the exposed end of the pencil, which cover must be large enough to cover the operating slot of the holder to prevent dust and dirt from finding access thereto 35 through and thus contaminating the pencil.

The device of my invention overcomes all of the above, and other, objectionable features and presents a compact device of inseparable parts in which the cosmetic pencil is 40 protected from contamination and which contains both a mirror and a pencil capable of coordinate use while employing but one hand.

The above-mentioned, and other, new and 45 valuable features of my device will be evident upon a consideration of my specification and its accompanying drawings.

In the accompanying drawings illustrating one form of the device of my invention similar parts are designated by similar numerals.

Figure 1 is a perspective view of one form of my device in closed position.

Figure 2 is a rear view of Figure 1.

Figure 3 is a section through the line 3—3 of Figure 1. 55

Figure 4 is section through the line 4—4 of Figure 1.

Figure 5 is a view of my device in open position, the extended position of the cosmetic-pencil and co-acting parts being shown 60 in dotted lines and indicated by prime numerals.

Figure 6 is an end view of Figure 5.

The particular form of the device of my invention shown in the accompanying drawings comprises a cosmetic pencil-carrying member having the base 10, the rear flange 11 and the end flanges 12 and 13. A fixed plate 14 is spaced slightly from the base 10. Pivotally attached at 15 to the plate 14 and capable of being positioned within the pencil-carrying member is a pencil container 16, open at its free end 17 and having a longitudinal slot 18 therein. Within the pencil container 16 is a cosmetic pencil 19 carried by the longitudinally movable cup 20 having a button 21 extended through the slot 18 to allow of the longitudinal movement of the pencil 19. 70

A mirror-carrying member comprises the base 22 having the front flange 23, the rear flange 24, and the end flanges 25 and 26, the rear flange 24 being hingedly attached to the rear flange 11 of the pencil-carrier, a mirror, or reflecting material, 27 is carried upon the inner face of the base 22. 80

In the device shown, the front edge of the base 10 abuts upon the upper edge of the front flange 23, when the device is in closed 85 position.

The illustrated means for maintaining the device in closed position comprises the lip 28 hingedly attached to the base 10 of the pencil-carrying member having a hole 29 therein capable of receiving the pin 30 of the front flange 23 of the mirror-carrying member. 90

The extended stop 31 carried by the rear flange 11 and the extended stop 32 carried by the rear flange 28, limit the movement of the pencil-carrying member and of the mirror-carrying member. 100

ror-carrying member upon their hinged connection.

The operation of the device is as follows:— The device when closed is in the position shown in Figures 1 to 4 inclusive, with the pencil container being positioned within the device.

When it is desired to use the cosmetic pencil, the device is opened, the pencil container 16 is pivotally revolved until it assumes the position 16' in Figures 5 and 6, and the cosmetic pencil 19' extended from within the pencil container by moving the button 21'.

The mirror-carrying member is then inclined to such an angle, that when the pencil 19 is applied to the lips of the user, the operation will be visible within the mirror 27.

The stops 31 and 32 may be so positioned that when the device is in fully opened position, the mirror will be properly placed for the purpose mentioned.

It will thus be seen that my invention presents a device of compact form in that it is but slightly larger than the cosmetic pencil, in which the cosmetic pencil is hygienically protected from dust or contact with other surfaces and in which the operation of the application of the pencil can be viewed while holding the device in one hand.

My device, therefore, comprises a cosmetic pencil and a mirror so combined with each other as to allow of their coordinate employment without disengaging the pencil from the device.

I do not limit myself to the particular size, shape, number or arrangement of parts as illustrated and described as these are given simply as a means for clearly describing the device of my invention.

What I claim is:—

1. In a device of the character described, in combination; a cosmetic pencil-carrying member; a mirror-carrying member hingedly attached to the pencil-carrying member, the mirror-carrying member and the pencil-carrying member forming an enclosure when in closed position; a pencil-container positioned centrally of the pencil-carrying member, pivotally attached thereto and capable of movement within a plane parallel to the face of said pencil-carrying member, and a mirror carried by the inner face of said mirror-carrying member.

2. In a device of the character described, in combination, a cosmetic pencil-carrying member; a mirror carrying member hingedly attached to the pencil-carrying member, the mirror-carrying member and the pencil-carrying member forming an enclosure when in closed position: a pencil-container pivotally carried within the pencil-carrying member capable of movement within a plane parallel to the face of said pencil-carrying member; a mirror carried by the inner face of

the mirror-carrying member, and means limiting the hinged movement of the mirror-carrying member so that the extremity of the pencil-container will be visible to a person applying said extremity to the lips of the observer.

3. In a device of the character described, in combination, a cosmetic pencil-carrying member; a mirror-carrying member hingedly attached to the pencil-carrying member; the pencil-carrying member and the mirror-carrying member forming an enclosure when in closed position; a pencil-container pivotally carried by the pencil-carrying member, capable of movement in a plane parallel to the face of said pencil-carrying member and capable of extension beyond said pencil-carrying member when the device is in open position, and a mirror carried by the inner face of said mirror-carrying member.

4. In a device of the character described, in combination, a cosmetic pencil-carrying member; a mirror-carrying member hingedly attached to said pencil-carrying member, the two said members forming a compartment when the device is in closed position, a pencil-container pivotally carried within said pencil-carrying member and movable in a plane parallel to the faces of both the pencil-carrying member and the mirror-carrying member when the device is closed and movable in a plane parallel to the face of the pencil-carrying member when the device is opened, and a mirror carried by the inner face of the mirror carrying member.

Signed at New York city in the county of New York and State of New York this 2nd day of July, 1928.

ANDREW GRAHAM SHIELDS.
